JOSEPH V. PETRELLI, OF GREENWICH, CONNECTICUT, ASSIGNOR OF ONE-TWENTIETH
TO FRANK J. KENT, OF NEW YORK, N. Y.

RAZOR-BLADE STROPPER.

Application filed May 6, 1925. Serial No. 28,283.

This invention relates to a device for sharpening razor blades.

A general object of the invention is to provide an improved razor blade stropping device of the general type in which a pair of adjacently placed rollers are engaged in alternation by an interposed blade which is swung intermittently from engagement with one roller to engagement with the other.

The invention includes a hand crank mechanism having a one-way driving connection with one of the rollers, a connecting link between the rollers for bringing about the rotation of the other roller in the opposite direction, and means for supporting and moving a blade alternately into engagement with the respective rollers.

A feature of the invention resides in a rock arm connection between the roller connecting link and the blade carrier which functions both to rock the carrier and to control the motion of the roller connecting link to produce rotation of the rollers in opposite directions.

Other features of the invention will be hereinafter referred to.

In the drawings, in which a preferred embodiment of the invention has been selected for illustration:

Figure 1 is a perspective view of a razor blade stropping device embodying the invention.

Figure 2 is a view in transverse section and on an enlarged scale of the device shown in Figure 1.

Figure 3 is a view in longitudinal section of the device shown in Figure 2.

Figure 4 is an end view of the device shown in Figure 1.

Figure 5 is a view in end elevation of the other end of the device shown in Figure 1.

Figure 6 is a sectional view through a stropping roller forming part of the device and showing driving means therefor.

Figure 7 is a view in cross-section looking in the direction of the arrows of Fig. 6 and showing a clutch device forming part of the driving means shown in Figure 6.

Figure 8 is a perspective view showing a blade holding device forming part of the invention, the parts thereof being in disassembled relation.

Figure 9 is a view similar to Figure 8

showing another form of blade holding device.

Figure 10 is a view similar to Figure 7 showing another form of clutch device that may be used with the invention.

Referring to the drawings for a more detailed description of the invention, a razor blade stropping device is shown which includes a casing or shell 10 having a substantially triangular formation in cross-section. The shell or casing 10 is attached at its ends to a rearward frame member 11 and a forward frame member 12 to thereby produce a substantially closed casing or housing for the operating parts.

The forward end plate 12 has mounted thereon in a journaled relation thereto a pair of blade stropping rollers 13 and 14 provided with leather-faced peripheries for producing the stropping effect on the blade being operated upon. The rollers 13 and 14 are spaced a slight distance apart and extend in a parallel relation from the end plate 12 on which they are supported by the projection of threaded extensions 15 carried by the rollers through the end plate 12 and on which clamping nuts 16 are mounted.

In order to drive the rollers a crank handle 17 is attached to the projecting end of a shaft 18 which is journaled in a sleeve 19 which terminates in the extension 15 already referred to. The inner end of the shaft 18 is provided with a ball raceway 20 in which a ball 21 is received. The roller structure includes a tubular member 22 which encloses the sleeve 19 and the raceway 20 and ball 21. Formed in the inner surface of the tubular member 22 is a cam groove 23 which forms with the ball member 21 a clutch device. Viewing the clutch as represented in Figure 7 of the drawing rotation of the shaft 18 in a counter-clockwise direction will not produce rotation of the roller 13 since the ball 21 will merely rotate on its own axis in contact with the shoulder 24 provided in the cam groove 23.

On the contrary rotation of the shaft in the other direction will cause a wedging or jamming of the ball member 21 between the converging surfaces of the cam groove and the raceway 20 to thereby bring about rotation of the roller 13 in the desired direction. By this construction rotation of the rollers can be brought about in only one direction there-

by obviating a reverse direction of rotation of the rollers with a resulting injury to the roller surfaces brought about by engagement of the surfaces with the cutting edge of the 5 blade.

In order to rotate the companion roller 14 a connecting rod or link 25 is provided which has pivotal engagement with the rearward end portions of the respective rollers 10 13 and 14. A rock arm 26 attached to a shaft 27 journaled in the rearward end wall 10 of the casing provides a directing or control member for producing a crank motion which will cause the roller 14 to be rotated 15 in exact accordance with the rotation of the roller 13 and in a reverse direction so that the confronting faces of the two rollers 13 and 14 rotate in an upward direction as viewed in Figures 2 and 5 of the drawing. 20 The shaft 27 already referred to forms part of a U-shaped frame member 28 which has a terminal portion 29 journaled in the forward frame plate 12 of the casing of the device. The frame member 28 is adapted 25 to carry a blade 30 and through its connection with the rock arm 26 the frame 28 rocks from side to side to move the blade edge into engagement alternately with the respective rollers 13 and 14. The rock arm 30 26 therefore performs two functions—it serves to control the operation of the connecting link 25 which connects the rollers 13 and 14 and it also serves to rock the frame or carriage 28 on which the razor blade is mounted. 35

The arm 26 is not directly keyed to shaft 27, but a friction washer 27^a of fiber or other suitable material is compressed between arm 26 and frame 28. This friction 40 drive causes frame 28 to follow the oscillatory movement of arm 26, but permits the arm 26 to continue movement in either direction after the razor blade has engaged one of the stropping rolls.

45 The simple and direct drive mechanism thus provided not only rotates the rolls in opposite directions, but also moves the blade into engagement with the appropriate roll and holds it in such engagement for the proper length of time.

The frame 28 is provided with a tubular member 31 in which is received a blade holding device such as that shown in Figure 8 of the drawings or as that shown in 50 Figure 9. The blade holding device shown in Figure 8 is made up of a holding bar 32 provided with a knurled thumb-piece or handle member 33 and having projecting lugs 34 adapted to enter corresponding recesses 35 in a companion holding bar 36 between which a double-edged blade such as is shown at 30 is adapted to be clamped. The holding bars 32 and 36 are held in their blade clamping relation by the insertion of 55 the assembled parts into the tubular portion

31 of the rock frame 28. An opening or recess 37 in the forward end plate 12 of the device provides for the insertion of the blade holding parts into the rock frame or their removal therefrom as may be required. 70 It will be clear that the reversal of the position of the blade in the tubular member 31 provides for the carrying out of the stropping operation on both of the blade edges.

75 Referring to Figure 9 of the drawings a blade holding device for blades of the type having but one edge and a reinforced back is provided. This device consists of a tubular member 38 having a handle member 39 and provided with a longitudinally extending slit 40 therein. The tubular member 38 is open as at 41 at one end and is adapted to receive therein a smaller tubular member 42 also slotted as at 43. A blade 44 having a reinforced rearward edge 45 is adapted to have the reinforced edge 45 inserted into the smaller tubular member 42 and the tubular member 42 is then inserted into the larger tubular member 38 to provide an assembled structure which can be placed into 80 position within the tubular portion 31 of the rock frame 28 as already described.

85 In order to facilitate the operation of placing a razor blade in position on the device or removing it therefrom, a thumb-piece 46 is provided on the shaft 27 by means of which the rock frame member 28 may be suitably centered to bring about the placing of the blade holder in position without injury to the adjacent roller surfaces. 90

95 In order to hold the end plate members 11 and 12 in position and in rigid relation to each other a pair of spacing members 47 are provided which are attached at one end to the inner surface of the forward plate 12 and at the other end are engaged by 100 screws 48 passing through the rearward wall 11.

105 Referring to Figure 10 of the drawings a modified form of clutch device is shown in 110 which a drive shaft 49 is provided with a race member 50 having an eccentric formation and rotatable inside the tubular portion 22 of the roller 13. In this form of the invention a pin 51 carried by the sleeve 22 115 engages a ball member 21 when rotating in a clockwise direction to bring about idle rotation of the shaft 49 without corresponding rotation of the roller 13. It will be seen that rotation of the shaft 49 in the reverse or counter-clockwise direction will cause the thickened portion of the eccentric 120 50 to wedge the ball 21 against the inner surface of the tubular member 22 and thereby rotate the tubular member and roller 13 125 with the shaft 49.

130 In order to prevent the engagement of the blade with the same section of the peripheral surfaces of the rollers provision is made changing the pivotal connection of the link

member 25 with the ends of the rollers 13 and 14. For this purpose recesses 52 formed in multiple, three being shown in the drawing, are provided in which inwardly extending lugs 53 on the link member project. The lugs are held in place in the recesses by the adjacency of the end wall 11 to the movable parts.

In the operation of the device it will be seen that rotation of the crank handle 17 in a clockwise direction as shown in Figure 1 will rotate the corresponding roller 13 in the same direction whereupon the link member 25 will rock about its pivotal connection with the rock arm 26 to thereby produce rotation of the roller 14 in the opposite direction. At the same time the endwise movement of the link member 25 produces a rocking movement of the rock arm 26 thereby 20 rocking or oscillating the frame 28 to move the edge of the blade 30 into alternate engagement with the respective rollers 13 and 14.

I claim:-

1. A razor sharpening device comprising a frame, a pair of parallel rollers mounted in the frame, means for rotating one of the rollers, a link member pivotally connected to an end of each roller, an arm having one end pivotally connected to the intermediate part of the link and its other end pivoted to the frame, a member for supporting a razor blade with an edge disposed between the rollers, and means for causing said arm

to rock the blade supporting member to 35 move the blade edge into contact with the rollers alternately.

2. A razor sharpening device comprising a frame, a pair of parallel rollers mounted in the frame, means for rotating one of the 40 rollers, a link member pivotally connected to an end of each roller, an arm having one end pivotally connected to the intermediate part of the link and its other end pivoted to the frame, a member for supporting a razor 45 blade with an edge disposed between the rollers, and a friction member engaging the arm and the blade supporting member to cause said arm to rock the blade supporting member to move the blade edge into contact 50 with each roller alternately.

3. A razor sharpening device comprising a frame, a pair of parallel rollers mounted in the frame, a hand crank for rotating one of the rollers, a one-way clutch connecting the crank to the roller, a link member having 55 its opposite ends pivotally connected to each roller, a blade supporting frame pivotally mounted in the frame, an arm having one end pivoted on the axis of the blade supporting-member and its opposite end pivotally connected to the intermediate part of the link, and a friction washer mounted on the axis of the blade-supporting member and 60 engaging the arm and the blade-supporting member.

In testimony whereof I affix my signature.
JOSEPH V. PETRELLI.
